SHADE HOLDER

Filed May 29, 1930

UNITED STATES PATENT OFFICE

CHARLES J. AUSTIN, OF UTICA, NEW YORK, ASSIGNOR TO ROBERT E. ROBERTS, OF UTICA, NEW YORK

SHADE HOLDER

Application filed May 29, 1930. Serial No. 457,452.

This invention relates to a shade holder and in certain forms of the invention to a shade holder and a curtain holder combined.

The purpose of this invention is to provide an article of the class described which is of new, improved and convenient construction.

Further purposes are to provide a shade holder or a shade and curtain holder which will provide in one structure bearings for the shade roller, a body to support such bearings, preferably removable and also adjustable both longitudinally and revolubly, a body to enclose the roller and the portion of the shade rolled thereon and means to prevent the shade from accidentally being drawn too far up on the roller or from going over the top of the roller and in the full form of the construction to combine with such unit a means for removably and replaceably supporting the top of a curtain immediately in front of the depending shade.

A further purpose is to provide a structure of the class described which is simple and economical in construction and free from unsightly exterior mechanical devices so that the article need not be concealed but will harmonize with the woodwork or other finishing of a room and protect the top of a shade and curtain instead of requiring those parts to hide the fixtures.

Fig. 1 is a front view of a shade holder embodying my invention, parts at both ends of the holder being broken away to show the construction, the right end member being shown as adjusted outwardly.

Fig. 2 is a vertical sectional view on line 2—2 of Fig. 1 and Fig. 3 is a similar sectional view on line 3—3 of Fig. 1. Fig. 4 is a front view of a shade holder and curtain holder embodying my invention and Fig. 5 is a left hand end view thereof 5—5 of Fig. 4.

Referring to the drawings in a more particular description and first to the shade holder alone shown in Figs. 1 to 3, it will be seen that the casing as a whole comprises a tubular portion 10 with front and rear depending strips or flanges 11 and 12. This casing preferably will be formed from a piece of sheet metal of suitable character and strength formed so as to produce the tubular portion

10 with the two strips 11 and 12 depending from the tubular portion towards the rear of the tube as seen in Figs. 2 and 3 and so as to leave between said strips a downwardly opening outlet 13 through which the depending portion of the shade 14 will extend from the shade roller 15 within the casing. Preferably the rear depending strip 12 will extend straight down from a point opposite the center of the tubular portion 10 and the lower part of said tubular portion will extend nearly to this rear strip 12 from which point the front strip 11 will extend downward. Preferably the lower edges of strips 11 and 12 will be turned upwardly to form a smooth and stronger edge for said strips. The front strip 12 will have this extra thickness to the front and the back strip will have this extra fold at the back. Near the opposite lower ends of both strips 11 and 12 opposite screw-receiving holes are provided. Loosely through this front hole there extends a screw 16, the threaded shank of which engages the screw-threaded hole in the back strip 12. These screws afford convenient and effective means for having the opposite ends of the tube 10 securely and adjustably but removably hold the ends 17 and 18 at the right and left hand ends respectively of the shade holder. These two ends are formed alike except that the right hand end 17 has in its inner plate 19 a centrally disposed round hole to receive the usual round pin 20 at the right end of the regular shade roller, while the inner plate 19 of the left hand end 18 has a vertically arranged centrally located slot 21 to receive the flat finger 22 usually provided upon the left hand end of a shade roller. Preferably the two ends 17 and 18 are formed with a cylindrical cup-shaped member 23 having an outwardly extending small rib 24 a short distance in from the outer extremity of the cup. The inner part of the encircling walls of the cup are turned over outside the inner plate 19 substantially as shown in Fig. 1 and the two parts of the end are suitably permanently secured to each other as by soldering or other means. The low rib 24 forms a convenient stop to prevent the ends 17 or 18 being inserted too far into the tube. A convenient way of assem-

85
90
95
100

bling the article is to insert the left hand end 18 in the proper position within its end of the tube 10 whereupon the screw 16 at that end of the holder is screwed in sufficiently to draw the front and rear strips 11 and 12 together thus contracting this end of the tube 10 tightly upon the end 18. The shade roller 15 with a shade 14 thereon is then inserted in the tube from the open right hand end and with the lower hemmed end 26 of the shade with its usual bottom wooden strip 27 in the hem of said lower end of the shade projecting out through the outlet 13 and below the strips 11 and 12. Then the right hand end 17 is inserted in that end of the tube. When the shade roller and shade thereon are thus inserted in the tube it will be understood that the flat finger 22 will be inserted in the slot 21 in the left hand inner plate 19. When the right hand end 17 is put in position the pin 20 at that end of the shade roller will project into the circular central opening 28 provided upon the inner plate 19 of this end. Then the right hand screw 16 will be inserted in the strips 11 and 12 and screwed up until the right hand end 17 is securely held in place.

Back of the casing there will be provided one long or several short spaced angular brackets 29 in the horizontal arm of which will be provided holes by means of which the whole device may be readily secured to the window frame in an obvious manner.

It will be understood that the depending strips or flanges 11 and 12 are spaced far enough apart to provide the vertical outlet 13 of sufficient depth to allow the shade 14 to move down therethrough readily.

Preferably a thick washer 30 as of rubber or like material readily formed from a short piece of tubing will be inserted upon the shank portion of the holding screws 16 between the flanges 11 and 12 so as to protect the edges of the shade 14 from being injured by coming in contact with the metal of the screws especially as the shank of said screws are threaded and so present a roughened surface to the edge of the shade.

Preferably the bearing 25 provided in the inner plate 19 of the right hand end 17 to receive the circular pin 20 at the right hand end of the shade roller will be formed integral with said plate 19 by drawing out the material from said plate to the right when the hole is formed in said plate as particularly appears in Fig. 1.

The construction so far described furthermore provides an opportunity for revolvably adjusting the left hand end 18 in its end of the casing by temporarily loosening the holding screw 16. This revolvble adjustment of this end allows said end to be rotated in either direction as may be necessary so as to carry around therewith the flat finger 22 at the left hand end of the shade roller within the casing so as to wind up further or so as

to unwind the re-winding spring 31 commonly used for re-winding shades of this type after they have been drawn down from the shade holder. This tightening up or loosening of the spring it will be obvious can be accomplished by rotating the left hand end 18 without having to take down the shade holder from the window and without having to remove the shade or shade roller from the casing and without having to disengage the end 18 from the flat finger 22 of the shade roller. This revolvble adjustment of the left hand end 18 it will be obvious could not be obtained were the end permanently attached to the casing or attached by means that would allow of the end being attached to the shade roller in only one position or were this end attached to the casing by bodily screwing this end on to the casing. In the latter case revolvble adjustment of the end might be obtained, but it would result in a longitudinal shifting of the position of the end relative to the casing.

Preferably I provide that the removable ends 17 and 18 be also longitudinally adjustable relative to the casing for a considerable extent. This longitudinal adjustment adapts the end to be set inwardly or outwardly within the range of adjustment so as to adapt the device to shade rollers that are normally of a given length, but which actually in practice often vary sufficiently to require setting of the bearings for the pin 31 or for the flat finger 22 farther apart or sometimes nearer together than would apparently be required for a shade roller of a given length. Such longitudinal adjustment also allows a given casing to be adapted to shade rollers of appreciably different lengths. That is a casing nominally built to fit a shade thirty inches wide may have its ends adjusted inwardly to fit the shade roller of a shade that is twenty-eight or even twenty-six inches wide or a shade casing where the ends at their inner adjustment would fit the shade roller of a twenty-eight inch shade may be adapted to be used with a shade that is thirty or even thirty-two inches wide by moving the ends outwardly relative to the casing. This longitudinal adjustment of the ends is obtained through the barrel or cylindrical part of the cup-shaped members 23 being made appreciably longer than would be required were the ribs 24 always to be at the inner position against the end of the casing. For instance, instead of the cylindrical part of an end inside the rib 24 being three-eighths or one-half of an inch in extent which would be enough simply for holding the end in place, said cylindrical part might be made an inch and a half or two inches or even two and one-half inches long as may be desired. By temporarily loosening the holding screws 16 the ends 17 or 18 may be pushed in or drawn out relative to the casing to fit the shade holder

to be used therein. In Fig. 1 of the drawings for the purpose of illustrating this extendible feature, the right hand end is shown in extended position and the left hand end is shown in inward position. It will be understood of course that in practice in general the adjustment will be made equally at both ends so as to maintain the symmetry of the device and the relative appearance of the shade and shade holder.

In the form of the invention shown in Figs. 4 and 5 the piece of sheet metal which is to provide the rear flange 12, the cylindrical part 10 of the casing and the forward flange or strip 11 is made or cut sufficiently greater so as to provide below the front flange 11 an extension bracket 32 slanting forwardly and preferably slightly downwardly and then curved downwardly and inwardly forming a second tubular casing 33. This casing is of gradually reduced diameter so that below the flat bracket portion 32 there is an opening 34 into the chamber proper 35 of the casing 33. The extremity of the metal inside this tube is bent sharply inwardly as shown in Fig. 5 for about half of the smaller diameter of the casing forming the inwardly projecting tongue 36. This lower tubular casing is as will be seen to hold the upper or hemmed portion of a window curtain 37. Through the pocket 38 formed by the hem in this curtain is thrust the angular shaped curtain bar 39 as shown in Fig. 6. The upper end of the window curtain 37 is assembled upon its holder, namely the casing 33, by passing the hemmed end of the curtain with the curtain bar 39 therein to the rear, that is to the left of the casing 33 as the parts are seen in Fig. 5 and then turning the upper extremity of the curtain forwardly through the opening 36 and continuing this movement in a circular direction until the curtain bar comes to the position shown in Fig. 5.

What I claim as new and desire to secure by Letters Patent is:

1. A shade and a curtain holder comprising a body having two spaced parallel tubes the first tube having an opening in its lower side for the shade to extend therethrough and having end bearings adapted to support the shade roller, the second tube being spaced forward of the outlet of the first tube having an opening at its rear side, a curtain bar adapted to be inserted in the top hem of the curtain and adapted when carrying said hem to be inserted through the outlet of the second tube and to rest in said second tube and hold the top of the curtain in said tube, but admitting of the removal of said top of the curtain and said curtain bar from said tube.

2. A shade and a curtain holder comprising a body having two spaced parallel tubes the first tube having an opening in its lower side for the shade to extend therethrough and

having removable end bearings adapted to support the shade roller, the second tube being spaced forward of the outlet of the first tube having an opening at its rear side, a curtain bar adapted to be inserted in the top hem of the curtain and adapted when carrying said hem to be inserted through the outlet of the second tube and hold the top of the curtain in said tube but admitting of the removal of said top of the curtain and said curtain bar from said tube.

3. A shade and a curtain holder comprising a body having two spaced parallel tubes, the first tube having an opening in its lower side for the shade to extend therethrough and having end bearings adapted to support the shade roller, the second tube being spaced forward of the outlet of the first tube having an opening at its rear side, a curtain bar V-shaped in cross section adapted to be inserted in the top hem of the curtain and adapted when carrying said hem to be inserted through the outlet of the second tube and to rest in said second tube and hold the top of the curtain in said tube but admitting of the removal of said top of the curtain and said curtain bar from said tube.

4. A shade holder comprising an open-sided and open-ended tubular casing adapted to house a shade roller and a shade thereon and having opposing spaced flanges at the edges of said side opening, end members removably mounted in the ends of said casing and having bearings to engage the shade roller pins, means engaging the opposite casing flanges near their ends for contracting the casing to hold the said end members therewith.

5. A shade holder comprising an open-sided and open-ended tubular casing adapted to house a shade roller and a shade thereon and having opposing spaced flanges at the edges of said side opening, end members removably mounted in the ends of said casing with longitudinal adjustment therein and having bearings to engage the shade roller pins, means engaging the opposite casing flanges near their ends for contracting the casing to hold the said end members therewith.

6. A shade holder comprising an open-sided and open-ended tubular casing adapted to house a shade roller and a shade thereon and having opposing spaced flanges at the edges of said side opening, and members removably mounted in the ends of said casing with longitudinal and revoluble adjustment therein and having bearings to engage the shade roller pins, means engaging the opposite casing flanges near their ends for contracting the casing to hold the said end members therewith.

7. A shade holder comprising an open-sided and open-ended tubular casing adapted to house a shade roller and a shade thereon

and having opposing spaced flanges at the edges of said side opening, end members removably mounted in the ends of said casing and having bearings to engage the shade roller pins, adjustable means engaging the opposite casing flanges near their ends for contracting the casing to hold the said end members therewithin.

8. A shade holder comprising an open-sided and open-ended tubular casing adapted to house a shade roller and a shade thereon and having opposing spaced flanges at the edges of said side opening, end members removably mounted in the ends of said casing and having bearings to engage the shade roller pins, screw-threaded means engaging the opposite casing flanges near their ends for contracting the casing to hold the said end members therewithin.

20 In witness whereof I have affixed my signature, this 24th day of May, 1930.
